BOTTLE OR SIMILAR ARTICLE

Robert A. Reintsema, Lancaster, Ohio, assignor to Anchor Hocking Glass Corporation, Lancaster, Ohio, a corporation of Delaware

Filed Nov. 9, 1965, Ser. No. 38,054

Term of patent 14 years

(Cl. D58—6)

FIG. 1 is a perspective view of a bottle or similar article showing my new design;

FIG. 2 is a side elevational view, the opposite side being the same in appearance as the side shown;

FIG. 3 is an elevational view looking from the right of FIG. 2, the opposite side being the same in appearance as the side shown; and

FIG. 4 is a fragmentary sectional view taken on the line 4—4 of FIG. 2.

The dominant features of my design reside in the portion shown in full lines.

I claim:

The ornamental design for a bottle or similar article substantially as shown and described.
